(57) **CLAIM**

The ornamental design for a lock for bicycle, as shown and described.

DESCRIPTION

FIG. 1 is a front perspective view of the lock for bicycle showing our new design;

FIG. 2 is a front view thereof where the rear view is a mirror image;

FIG. 3 is a left side view thereof;

FIG. 4 is a right side view thereof;

FIG. 5 is a top plan view thereof;

FIG. 6 is a bottom plan view thereof;

FIG. 7 is an exploded perspective view thereof; and,

FIG. 8 is a perspective view thereof, showing the claimed design in use.

The broken lines depict environment of the lock for bicycle that forms no part of the claimed design.
